UNITED STATES PATENT OFFICE.

THOMAS L. PARKER, OF CHICAGO, ILLINOIS, ASSIGNOR TO THE STANDARD ELECTRIC MANUFACTURING CO., OF CHICAGO, ILLINOIS, A CORPORATION OF ILLINOIS.

MAIL BOX.

Application filed October 4, 1924. Serial No. 741,700.

My invention belongs to that general class of devices known as mail boxes and the like, and relates more particularly to a box or boxes for use in office buildings, residences, 5 apartments and the like, for receiving mail, or for such other uses as it may be found adapted. The invention has among its objects the production of a device of the kind described which is simple, compact, convenient, durable, reliable, attractive and 10 satisfactory for use wherever found applicable. More particularly it relates to a mail box of large capacity in which the carrier may deposit letters, cards, magazines, and 15 even packages conveniently and rapidly, and in which the contents will be fully and completely protected until removed by the individual box owner or occupant. It has particularly as an object the construction where- 20 in the carrier may open the boxes with a master key by unlocking one lock and deposit the mail for all of the boxes in the separate boxes and then lock the same up, and the individual owner may then open his individual box and 25 have access to his individual mail. It is also constructed so that peddlers, canvassers and distributors generally cannot deposit circu- 30 lars, samples and undesirable matter to the annoyance of the box holder. It has also as an object the production of a box in which the contents are entirely protected from dust, dirt and the weather. Among its further ob- 35 jects is the production of a box of the kind described which is preferably made up in a series of units, one or more of which may be 40 associated and secured together so as to form a unitary construction consisting of the desired number of boxes arranged in sets or banks. Many other objects and advantages 45 of the construction herein shown and de- 50 scribed will be obvious to those skilled in the art from the disclosures herein given.

To this end my invention consists in the novel construction, arrangement and combination of parts herein shown and described, 45 and more particularly pointed out in the claims.

In the drawings, wherein like reference characters indicate like or corresponding 50 parts:

Fig. 1 is a front elevation of a bank of boxes;

Fig. 2 is a top elevation of the same;

Fig. 3 is a sectional view taken substantial- 55 ly on line 3—3 of Fig. 1;

Fig. 4 is an enlarged sectional view taken substantially on line 4—4 of Fig. 2;

Fig. 5 is a sectional view taken substantially on line 5—5 of Fig. 4;

Fig. 6 is a sectional view taken substantially on line 6—6 of Fig. 4;

Fig. 7 is a sectional view taken substantially on line 7—7 of Fig. 1; and

Fig. 8 is a sectional view taken substantially on line 8—8 of Fig. 2.

Referring to the drawings, in which the preferred embodiment of the invention is shown, I have illustrated a bank of three boxes, it being understood that it is immaterial how many boxes make up a bank or set. It may likewise be mentioned that generally I prefer to make the same in units so that they may be installed with one, two or more units to make up the bank.

Referring particularly to Figs. 1 and 7, 75 1 represents a frame or face plate, which plate may be in common for all the boxes, or, as shown, individual for each unit. At the back of the face plate is a container 2 consisting of three walls and a bottom, together with a top (not shown), if desired, the face plate making the front wall. The particular plate shown is provided with inturned flanges 3 about a portion of the front door openings, as will be hereinafter described, and the outer edge is preferably rounded or turned back, as indicated at 4. The parts 2 are secured to the flanges 3 at the sides, top and bottom of the plate at the openings, and the several units secured together by the bars 5 and 6 extending across the bank and secured to the upper flange 3 and lower flange 6 at the door openings.

There are provided two sets of doors, one master locked, the key to which is carried by the mail carrier, and the other to which the box user has his individual key. The construction is such that the carrier may by unlocking one box simultaneously unlock others in the bank at the same time where there are several boxes in a bank, the individual box user being able to unlock only his own box.

As shown, the panel is provided with door openings 9 for the master doors 11, which are arranged to be locked and unlocked by the mail carrier, and with door openings 10 provided with individual doors 12 for each individual box user, each individual door being provided with its separate lock 13, while 105 110

the doors 11 are provided with a lock 14 in common. The doors may be hinged and supported in any suitable manner, the preferred construction consisting of a rod 17 for each unit, to which the doors are secured, the same constituting a hinge part. As shown, the edge of the door is wrapped around the rod so that the door is reinforced by the wrapped portion at the hinged edge, the opposite edges 10 being reinforced and stiffened by the flange thereat, as shown in Fig. 7. I have shown the three upper doors or carrier doors operatively connected together by a simple construction consisting of the arms 19 pivotally connected to a bar 20 and 21. Obviously, opening one door, for example the one which is locked, simultaneously opens the associated doors connected to the bar 20. As shown in Figs. 1 and 8, I have provided the center door with a lock 25, the same having a lock bar 24 which engages in a notch 23 in the bar 20; and the bar 22 may be also notched, the construction being such that when the lock bar 24 is in operative position as shown, 25 it engages in the notches 22 and 23 and prevents any movement of the bar 20.

I have also provided additional locking means for the doors 11 adapted to engage and lock the free edges, thereby preventing the door being bent at the hinges. As shown, each door is provided with a latching element 28 provided with a lug 29 adapted to engage with a notch 32 on a lock bar 30, the lock bar being cut away as indicated at 31 (see Fig. 4). The lock bars 30 are each slidably mounted on the flanges 3 at the door opening, a pin and slot connection 33-34 being shown. Each bar is provided with an extending portion 35, and preferably formed with the lugs 36-37. The extending portion 37 is secured to a bar 38 by screws 39 or equivalent means. The opposite extension 36 is slidably mounted on a post 40, a spring 41 being interposed between the extension 36 and the end of the post. The spring tends to force the bar 38 carrying the members 30 downwardly and maintain the same substantially as shown in the dotted lines in Fig. 4 when the boxes are unlocked. When the doors are shut, however, the box locked, the lock bar 24 is thrown upwardly and engages with the rod 38 (see Figs. 3 and 8), lifting bar 38 and with it the locking members 30. The lock bars 30 then engage with the lugs 29 and maintain all the doors closed and locked at their free edges.

It may be mentioned that the postal carrier may carry a master key for all the boxes on his route, the particular lock 25 being generally furnished by the Post Office Department, the requirements calling for an official lock.

Each of the lower doors is provided with an individual lock 44, and it may be mentioned that these locks are made in numerous

key changes to avoid the possibility of one user being able to open an adjacent box. It is not necessary to describe these locks in detail as they may be as desired, that shown being provided with a spring latch member 46 70 adapted to engage in a notch 45 in the flange portion 3 to which the part 2 is secured.

I have shown each of the individual boxes provided with a frame 46 so arranged that the name of the box holder may be placed thereon, with a space 49 in which the apartment number or letter or identifying character may be placed. The same are also shown provided with slots 50, and in this connection I prefer to make these slots only of such size that a card or the like may be inserted, thereby preventing canvassers, peddlers and other people from filling the box with circulars. The same is also provided with a sight opening 51, if desired, through which the user may observe whether or not there is any mail in the box.

The particular boxes shown are provided with speaking tube mouth pieces 52 and push buttons 53, 54 representing the shank extending back into which the bell wires are attached in the usual manner. Any equivalent constructions may be embodied in the boxes.

I have not considered it necessary to describe in detail how the box may be mounted, but in Fig. 1 I have illustrated at 55 a portion of the building wall or support made up as desired, and to which the casings may be secured by screws 56 or by bolts or any equivalent fastening means. It may be mentioned that I generally prefer to secure the lock 25 to the door by providing studs 25' on the door (see Fig. 5), which are threaded to receive nuts at the outer side of the lock body or casing. In case the lock does not function, it is a simple matter for the repair man to open the door of the compartment below to which the lock is applied and reach up and remove the nuts. Any equivalent fastening means, however, may be employed.

It will be noted by referring to Fig. 1, as well as Fig. 3, that the box is substantially double the length of the usual box, and is of a larger capacity. This permits the placing of large mail matter therein, such as 115 magazines, newspapers, packages, etc., not possible in present constructions.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the kind described and in combination, a receptacle provided with a plurality of doors and locking means for said

doors, the locking means for one door comprising a lock bar arranged at the free edge of the door and a controlling bar mounted at the top edge of the door, a sliding bar 5 operatively connected with the hinged edge of the door, and means carried by the door for locking said bars in operative locking position, said door provided with means at the free edge for engaging the lock bar adjacent thereto.

2. In a device of the kind described and in combination, receptacles provided with a plurality of doors and locking means for said doors, the locking means for each door including 15 a lock bar arranged at the free edge of the door and engageable therewith and a controlling bar common to all doors mounted at the top edge of the doors, a sliding bar operatively connected with the hinged edge 20 of the door, and means carried by one door for locking said bars in operative locking position, said door provided with means at the free edge for engaging the lock bar adjacent thereto.

25 3. In a device of the kind described and in combination, a plurality of receptacles, a cover arranged over the front thereof for forming one side of said receptacles, said cover provided with a plurality of door openings adjacent the upper part of the receptacle, doors at said openings hinged at one side thereof and lock controlled means for locking said doors in closed position at opposite sides thereof, said locking means operatively 30 connected with all of the doors whereby opening or closing or locking one door will simultaneously control the opening, closing or locking of the remaining doors, each receptacle provided with a door arranged below 35 said first-mentioned doors, each of said last-mentioned doors provided with its individual locking mechanism and operable independently of the other doors.

40 4. In a device of the kind described and in combination, a plurality of receptacles, a cover arranged over the front of each for forming one side of each of said receptacles, means for securing said receptacles together, said covers each provided with a plurality of 45 door openings adjacent the upper part of the receptacle, doors for said openings hinged at one side thereof and lock-controlled means for locking said doors in closed position at opposite sides thereof, said locking means 50 operatively connected with all of the doors

whereby opening or closing or locking one door will simultaneously control the opening, closing or locking of the remaining doors, each receptacle provided with a door arranged below said first-mentioned doors, 60 each of said last-mentioned doors provided with its individual locking mechanism and operable independently of the other doors.

5. In a device of the kind described and in combination, a series of receptacles, each of 65 which is provided with a door, a key-controlled lock associated with one of said doors, a bar operatively connected to said lock and controlling the opening and closing of all of said doors in unison, and additional locking means for said doors also acting in unison and controlled by said lock.

6. In a device of the kind described and in combination, a series of receptacles, each of which is provided with a door, a key-controlled lock associated with one of said doors, a bar operatively connected with said lock and controlling the opening and closing of all of said doors in unison, and additional locking means for said doors also acting and 80 controlled by said lock, said additional locking means engaging the free edges of said doors.

7. In a device of the kind described and in combination, a series of receptacles, each of 85 which is provided with a door, a key-controlled lock associated with one of said doors, a bar operatively connected to said lock and controlling the opening and closing of all of said doors in unison, additional locking 90 means for said doors also acting in unison and controlled by said lock, and a second door for each of said receptacles having independent locking means.

8. In a device of the kind described and in combination, a series of receptacles, each of which is provided with a door, a key-controlled lock associated with one of said doors, a bar operatively connected with said lock and controlling the opening and closing of 100 all of said doors in unison, additional locking means for said doors also acting in unison and controlled by said lock, said additional locking means engaging the free edges of said doors, and a second door for each of said receptacles having independent locking means.

In testimony whereof, I have hereunto signed my name.

THOMAS L. PARKER.
